UNITED STATES PATENT OFFICE.

ADAM H. PRENZEL, OF HALIFAX, PENNSYLVANIA.

MOLDED-FLANGE INSOLE.

Application filed July 9, 1925. Serial No. 42,544.

This invention relates to improvements in shoes, and it consists of the construction and process of manufacture of a particular shoe sole.

5 An object of the invention is to produce an upstanding flange substantially at the periphery of an insole by a molding or forming operation as appears more fully below, for the purpose of making room for 10 the stapling anvil of a lasting machine.

Other objects and advantages appear in the following specification, reference being had to the accompanying drawing, in which—

15 Figure 1 is a perspective view of a peripherally channeled and stamped insole.

Figure 2 is a cross section on the line 2—2 of Figure 1.

Figure 3 is a perspective view of the insole showing the channel flange after the insole has been subjected to one of the steps of the improved process.

20 Figure 4 is a cross section on the line 4—4 of Figure 3 illustrating the appearance 25 of the channel flange.

Figure 5 is a detail sectional view showing how the molded channel flange fits upon the anvil of a lasting machine.

Figure 6 is a detail sectional view illustrating a step in the sewing operation.

30 In Figure 1 the insole 1 is peripherally channeled as at 2 to provide a flange 3. The adjacent edge of the sole is also beveled as shown. This particular insole is employed 35 in making the welt and one of the steps in the manufacture of this type of shoe is to temporarily fasten an upper structure to the flange 3.

Upon consideration of Figure 2 it is readily 40 seen that the flange 3 makes intimate contact with the body of the insole 1. The loose or feather edge of the flange lies so close to the bottom of the channel 2 that considerable difficulty is experienced in fitting the flange upon the anvil of the lasting machine preparatory to getting the parts into position for the driving of staples, or other means by which the upper structure 45 is temporarily affixed to the flange.

50 It is a purpose of the invention to so

treat, mold or form the channel flange 3 that the act of fitting the shoe to the anvil of the lasting machine will involve no difficulty or problem at all. The invention resides not only in the process involved but 55 also in the product resulting therefrom.

Figures 3 and 4 illustrate the shape of the flange 3 after it has been treated. The flange is caused to stand up in relationship to the insole 1 and curves in respect to the insole 60 to provide a concavity 4. The insole is moistened preparatory to the step of treating, forming or molding the flange 3 so that it readily yields to the operation. Upon drying, the flange 3 retains the shape given to 65 it by the molding operation, the channel 2 and concavity 4 providing an ample pocket for the reception of the anvil 5 (Fig. 5) of a lasting machine. The feather edge 6 of 70 the molded flange presents the shape of a hook in cross section (Figs. 4 and 5) which makes it easy to fit the flange over the anvil. The common experience of drawing the bottom of the insole over the anvil 5 in order to find the channel is entirely avoided. 75

Figure 5 illustrates the flange 3 of the insole 1 in position upon the anvil 5 preparatory to the driving of the staple 7. The staple is driven through the flange as well as the lining 8 and leather 9 of the shoe 80 upper structure which is intended to be held in place temporarily. The stapling operation occurs prior to the inseaming operation illustrated in Figure 6. The needle 10 inserts the inseam through a welt strip 11, 85 the shoe upper structure and the base of the flange 3.

The curved, curled or concaved channel flange 6 may be given its shape by any means appropriate for the purpose, and a part of the invention therefore resides in the article itself. The insole is formed from a piece of leather by stamping, channeling, moistening and treating the resulting flange 3, and another part of the invention therefore resides 95 in the particular step of molding the channel flange into the particular shape described.

I claim:

A shoe sole having a channel cut from a 100

place interiorly of one side surface toward the edge producing a feather edge flange, said flange being in upstanding relationship to the sole and being cross sectionally curved so that the feather edge is spaced above the adjacent said surface of the sole and is directed toward the interior of the sole and

arched over the channel, the concaved interior of the flange and the bottom of the channel providing an ample peripheral ¹⁰ pocket accessible from the interior of the sole.

ADAM H. PRENZEL.
